UNITED STATES PATENT OFFICE.

CLIO B. YAW, OF ARLINGTON, NEW JERSEY, ASSIGNOR TO THE REMINGTON TYPE-WRITER COMPANY, OF ILION, NEW YORK, A CORPORATION OF NEW YORK.

TYPE-WRITING MACHINE.

1,167,963.

Specification of Letters Patent. Patented Jan. 11, 1916.

Application filed September 16, 1914. Serial No. 861,965.

To all whom it may concern:

Be it known that I, CLIO B. YAW, citizen of the United States, and resident of Arlington, in the county of Hudson and State of 5 New Jersey, have invented certain new and useful Improvements in Type-Writing Machines, of which the following is a specification.

My present invention relates to tabulating 10 mechanism for typewriting machines, and its general object is to provide new and improved mechanism of the character specified.

More specifically, one object of the invention is to provide novel column selecting 15 mechanism; another object is to provide novel denominational tabulating mechanism; and still another object is so to construct said novel mechanisms that they may be embodied in a single typewriting machine.

20 To the above and other ends, my invention consists in the features of construction, combinations of devices, and arrangements of parts hereinafter described and particularly pointed out in the claims.

25 In the accompanying drawings which illustrate the preferred form of my invention, Figure 1 is a fore and aft vertical sectional view of a typewriting machine embodying my invention, only so much of the 30 machine being illustrated as is necessary to a full understanding of said invention, and said figure particularly illustrating the denominational tabulating mechanism. Fig. 2 is a fragmentary rear elevation illustrating 35 the carriage feeding and releasing mechanism. Fig. 3 is a fragmentary detail view showing one of the denominational stop levers in operative position. Fig. 4 is a view corresponding to Fig. 1 but illustrating

40 more especially the column selecting mechanism. Fig. 5 is a fragmentary rear elevation illustrating certain parts of the column selecting mechanism. Fig. 6 is a fragmentary top plan view showing parts of both 45 mechanisms. Fig. 7 is a fragmentary top plan view, partly in section, illustrating the key connections of both the column selecting and denominational tabulating mechanisms. Fig. 8 is a fragmentary top plan view showing 50 certain parts of the column selecting mechanism in operative position. Fig. 9 is a corresponding view of the denominational tabulating mechanism.

As appears from Figs. 1 and 4, the main 55 frame of the machine comprises end plates 1

and a connecting top plate 2. Fixed to the rear portion of the main frame is a guide rail 3 grooved at its top and bottom to cooperate through anti-friction rolls 4 with a slide bar 5 comprised in a platen carriage, 60 which slide bar partly embraces the guide rail. Said carriage further includes bars 6 fixed to the bar 5 and extending upward therefrom. Said carriage, on which is mounted a rotary platen 7, is connected to a 65 motor or spring drum 8 supported on a frame 9 detachably secured to the end plates 1. The connections between said motor and said carriage comprise a gear wheel 10 concentric with the spring drum, said gear 70 wheel meshing with a set of teeth 11 on a rack bar 12 which is further provided with a second series of teeth 13 that mesh with a feed pinion 14 controlled by escapement devices, so that while the constant tendency of 75 the motor 8, acting through the described connections, is to draw the carriage leftward, this movement will be controlled by the printing keys acting through the escapement devices so long as the latter remain in 80 control of the feed pinion 14. Said feed pinion is loosely mounted on a shaft 15 which, as best appears in Fig. 2, is journaled upon the frame 9. A slidable clutch member 16 is mounted on the shaft 15 below the 85 pinion 14 and is provided at its upper end with ratchet or clutch teeth which mesh with corresponding clutch teeth on said pinion, said clutch member being normally retained in operative engagement by a spring 17 90 coiled around the shaft 15. The clutch member is caused to turn always when said shaft turns by reason of its engagement with notches formed in a flange 18 fixed to said shaft. The construction permits the 95 clutch member to be slid down along the shaft 15 to disengage from said pinion without disconnection from said shaft. Fixed to the lower end portion of the shaft 15 is a 100 toothed escapement wheel 19 with which co-operate escapement dogs 20 and 21 mounted on a rocker or carrier 22, which is fragmentarily shown in Fig. 1. Said dogs are controlled by printing keys, as disclosed in my pending application Sr. No. 855,551, 105 filed August 7th, 1914. To move the clutch member downward and release the carriage devices means are provided which co-operate with a circumferential groove 23 in said clutch member, as hereinafter described. 110

Both the column selecting and denominational stop devices that are key controlled coöperate with adjustably mounted carriage carried or column stops 24. Any desired 5 number of carriage stops 24 may be provided, these stops being notched to fit over a toothed stop carrying bar 25, which is journaled at its ends on arms 26, depending from the slide bar 5. Outside one of the 10 arms 26 the slide bar 25 is provided with a knurled finger button 27 (Fig. 9) by which it may be rotated to any one of a plurality of set positions. This construction enables a plurality of combinations or arrangements 15 of carriage stops 24 to be set along the bar and brought separately into use by rotating the bar 25 until the proper setting is obtained. The bar 25 is located so that during carriage movements it carries the column stops 24 between the denominational 20 stops, which are located at the front side of the bar, and the column selecting stop member, which is located at the rear side thereof, so that while the rear face or portion of each 25 carriage stop 24 may coöperate with the column selector to arrive at a predetermined columnar position, the front side of said stop may coöperate with the denominational stops to arrest the carriage in desired 30 denominational positions.

Both the column selecting and denominational stops are mounted on a detachable frame at the rear of the machine. A cross bar 28 extends from the bottom edge of one 35 end plate 1 to the other and is screwed to said end plates. Rising from said cross bar, to which it is detachably secured by screws 29, is a frame post or member 30 (Figs. 1 and 4-6). The denominational stop levers 40 are mounted to swing back and forth, as hereinafter described, in a series of parallel vertical guide slots 31 in the upper end portion of said member, which is also cut away, as indicated at 32, to provide a free passage- 45 way for the travel of the carriage stops.

The column selecting mechanism will next be described, reference being had especially to Figs. 4-8. Two parallel supporting arms or brackets 33 are screwed or otherwise secured to the post 30 and extend rightward therefrom, or toward the left when viewed from the rear. As seen in Fig. 6 each bracket fits around a corner of the post, having an angular extension 33^a which 50 engages the right-hand face of the post and is screwed thereagainst, thereby increasing the stability of the bracket. At its free end each bracket is curved rearward and is bored out to provide a bearing for an upright rod 55 or rock shaft 34, the ends whereof project beyond the bearings. Secured to the upper end of said shaft is a bell crank comprising a long arm 35, a short arm 36, and a hub portion 37, which hub portion receives a set 60 screw 38 by which the bell crank is secured

to the shaft. The lower projecting end of the shaft 34 receives an arm 39 provided with a collar 40 which surrounds the shaft and is suitably fixed thereto. The arm 39 is parallel with the arm 35 of the bell crank, 70 these arms extending leftward and providing at their free ends bearings for a vertical shaft 41. Secured to the upper end of the shaft 41 is a multiple column stop member, designated as a whole by the reference numeral 42, said member comprising a central cylindrical portion 43 from which radially project any desired number of teeth or stops 44. There are eight of these stops or contact devices 44 in the present instance and 80 the multiple stop is arranged at such a height that when swung forward, as hereinafter described, these contact devices will enter the path of the carriage stops 24. Preferably in the present instance the said 85 member further comprises a downward extension or hub 45 terminating in a ratchet or detent wheel 46, the whole member being suitably secured to the shaft so as to rotate therewith. The multiple stop is arranged 90 above the arm 35. Between said arm and the arm 39 the shaft 41 receives a hub or barrel member 47 which is partly hollow and is fixed to the shaft by one or more set screws. The barrel 47 is provided with a 95 series of radial projections or stops 48, these projections being arranged progressively both lengthwise of the barrel and circumferentially thereof.

A coiled spring 49 surrounds the shaft 41 100 and is partly housed within the barrel, the upper end of said spring being secured to the barrel while the lower end is anchored to the arm 39. The tendency of the spring is to turn the column selector, comprising 105 the barrel and the multiple stop, in the direction of the arrow in Fig. 5 and to maintain a stop pin 50 projecting upward from the barrel in contact with a downwardly projecting stop pin 51 on the arm 35. The other 110 bell crank arm 36 is provided with a pin 52 over which is hooked one end of a draw spring 53, the opposite end whereof is anchored to a pin 54 on the upper bracket 33. The tendency of this spring is constantly 115 to throw or swing the frame, comprising the shaft 34, the bell crank 35, 36, and the arm 39, together with the column selector carried by said swinging frame, toward the rear. The rearward swing, however, is limited by the pin 54 engaging with the forward end of a slot 55 formed in an angular extension 36^a of the arm 36 (Fig. 6). The forward swing of the frame and the stop devices or selector which it carries is limited 120 by the engagement of the rear end of the slot 55 with a stop pin 56 on the bracket 33 (Fig. 8). This forward swing is for the purpose of bringing said stop devices into operative position and is caused by horizon- 125 130

tal key controlled arms or actuators 57 which are arranged loosely one above the other on the shaft 34, being properly separated by washers 58. There are in the present instance eight of these actuators and their end portions are adapted each to engage with one of the projections 48, the actuator thus combining the junctions of an actuating device and a stop. When pulled forward each actuator is adapted to contact with a vertical rod 59, secured at its ends to the arms 35 and 39 somewhat to the right of the barrel 47, and through said rod 59 communicate movement to the swinging frame and stop devices. The actuators 57 are guided in their swinging movements by a slotted plate or comb 60 which is formed with a series of parallel horizontal guide slots to receive and guide the actuators, and is provided with ears 61 which receive headed screws 62 by which the comb plate is fixed to the brackets 33. Swinging movements are communicated to the actuators by trains of key controlled devices, one train being provided for each actuator and each train comprising a link 63 pivotally connected at its rear end to the actuator and extending forward and somewhat downward therefrom. The forward end of each link is pivotally connected to an upright crank arm 64 fixed to a rock shaft 65. There are eight of these rock shafts arranged in a series, one forward of the other at the front of the machine and below the keyboard, said rock shafts extending from side to side and being pivoted at their ends on pivot screws 65^a secured in supporting bars 66 which are provided with upwardly extending ears 66^a that receive headed screws 66^b whereby said bars 66 are detachably secured to the inner faces of the end plates 1. The rearmost rock shaft is connected through the described train to the uppermost or top actuator 57 and so on successively toward the front where the foremost rock shaft is connected to the lowermost or bottom actuator. As appears from Fig. 7 the crank arms 64 are arranged at progressively varying distances from the right-hand ends of their respective rock shafts 65 while the points of attachment of the links 63 to the actuators are in a vertical straight line, so that the links 63 fan or spread somewhat as they approach the front of the machine, thereby avoiding any chance of their interfering with each other when their keys are actuated. Close to its right-hand end each rock shaft is provided with a forwardly extending crank arm 67 to the free end of which is pivotally connected the lower end of an upright key stem 68, said key stem projecting upward through a guide opening in the keyboard cover or plate 69 and terminating in a button or key 70. The column keys 70 are at the right of the regular key-board (not shown), the set extending from top to bottom of the bank of keys and being suitably marked to indicate the column to which they correspond. Thus in the present instance the bottom key receives the number "1", the second key "2", and so on to the top key which bears the number "8". When any one of the column selecting keys 70 is depressed it acts through the train of connections comprising arm 67, 75 rock shaft 65, arm 64 and link 63 on the associate actuator 57, swinging the same forward on its axis 34 against the rod 59 and acting through said rod to move the swinging frame forward and bring 80 the contact devices or stops 44 into the path of the rear contact portions of the carriage stops 24.

Means are provided for automatically releasing the carriage by the column keys, 85 said means in the present instance comprising a U-shaped universal bar or bail 71 embracing between its end portions the post 30, said end portions being pivoted at 72 to the sides of said posts, the bail depending 90 at the front side of said post and carrying a cross rod 73 on which is loosely pivoted an arm or connecting link 74, said arm extending rearward and being twisted so that its rear portion is horizontal and may pass between 95 two of the actuators 57. This horizontal portion is formed with an elongated slot 75 which loosely embraces the rod 59, the construction being such that when the swinging frame is moved forward the rod 59, acting against the forward end of the slot 75, actuates the link or device 74, pushing the same forward and causing it to swing forward the bail 71, the rod 59 in this instance 100 acting as a universal bar. It may here be noted that the bail 71 and link 74 may however be swung forward without affecting the rod 59 and the swinging frame on which it is supported, by reason of the lost motion connection afforded by the slot 75 and rod 59. The forward swinging movement communicated to the bail 71 is transmitted to a link 76 which is connected to a projecting end of the rod 73 and extends upward to 105 its point of connection with an angular lever 77 which, as shown in Fig. 2, is pivoted at 78 to the frame 9, the opposite end of said lever being provided with a pin 79 which engages the circumferential groove 23. Said lever is also operative from a release key on the carriage. As the bail 71 swings forward the link 76 is pushed up, acting to swing the lever 77 on its pivot and causing the pin 79 to slide the clutch member 16 downward against the spring 17, thereby 110 freeing the carriage from the control of its escapement devices and allowing it to move uninterruptedly leftward under the pull of the spring drum 8. This release of the carriage is timed to take place just after the 115

120

125

130

multiple stop 42 is brought to operative position. Consequently as the carriage moves leftward the first column stop to the right of the multiple stop will contact with the 5 first stop device 44 and will turn the column selector a unit's distance in the direction of the arrow in Fig. 8, positioning the following contact 44 in the path of the next succeeding carriage stop. The selector is re- 10 tained in this position temporarily by devices comprising the detent wheel 46 and a detent or pawl 80 which is normally separated from the detent wheel but which is engaged thereby when the selector is swung 15 into operation. Said pawl is pivoted at 81 to a horizontal ledge on the post 30 (Fig. 6) and is retained in normal position in contact with a vertical face of said post by a spring 82 which is connected to the tail of 20 the pawl and is also anchored to the post. When in operation each unit turning movement of the multiple stop causes one of the ratchet teeth to pass the pawl 80 which then drops in behind the tooth and prevents any 25 backward turning movement under the influence of the spring 49. As the carriage moves leftward the operative column stops 24 will successively engage at their rear portion with successive projections 44 on the 30 multiple stop and will turn said multiple stop step-by-step as described, the step-by-step movement continuing until the operated actuator 57 is engaged at its free or stop end by the associate projection 48 on 35 the barrel 47. Since these projections are progressively arranged it will be understood that the extent of step-by-step turning movements of the multiple stop will depend on which one of the actuators is in operation. 40 Thus if the "1" column selecting key is operated, the actuator to which it is connected, *i. e.*, the lowermost actuator, will be swung forward and positioned in the path of the lowermost projection 48, so that the 45 selector cannot turn at all and accordingly the multiple stop will arrest the carriage when it is engaged by the first or proximate carriage stop 24. On the other hand, if the "8" column selecting key is operated it will 50 actuate or swing forward the uppermost actuator 57, bringing the same into the path of the uppermost stop or projection 48, and consequently the multiple stop will be turned successively step-by-step by the first 55 seven carriage or column stops which will pass freely by it without arresting the carriage, this arrest taking place only when the eighth carriage stop engages with the multiple stop, at which time the uppermost projection 48 will be in engagement with the end of the uppermost actuator. It will be understood that lesser extents of turning movement of the multiple stop and consequent arrest of the carriage at columnar positions preceding the eighth column will be

caused by operating the column keys between the "1" and "8" keys; that the columnar position of arrest will depend on the particular column selecting key that is actuated; and that all columns intervening between the position in which the carriage may be at the moment and the selected columnar position will be skipped or passed, the carriage running freely until arrested in the selected and predetermined column, 75 that is, so that the desired column on the work sheet carried by the carriage but not shown herein is opposite the printing point.

When the depressed column selecting key is released, the swinging frame and the stop or contact devices thereon will be swung back to normal position by the spring 53, and as soon as the ratchet wheel 46 is freed from the pawl 80 the shaft 41 and the devices mounted thereon will be rotated backward to normal position by the spring 49. At the same time that the other parts are returned, the actuator 57 and its key connections will also be returned to normal position by spring means, said means comprising for each actuator a coiled spring 83 which, as appears from Figs. 5-7, is hooked through a hole in an angular extension or tail portion 57^a of the actuator, the opposite end of the spring being anchored to a curved lug 84 formed on the upright plate 85 which is secured at its ends by screws 86 to the brackets 33. It will be understood that the lugs 84 extend in a vertical line lengthwise of the plate 85; that the restoring springs 83 are arranged one above the other; and that each spring is effective to return its actuator to the rear end of the guide slot in the comb 60 which acts as a stop. After the column selecting mechanism has returned to normal position it may again be actuated to cause the advance of the carriage to another columnar position without an operation of any of the printing keys or any preliminary advance movement of the carriage being necessary in order to clear the previously arrested carriage stop from the column selecting mechanism. This is a decided improvement over some prior constructions wherein it was necessary to operate several of the printing keys or to actuate the space bar several times in order to clear the arrested carriage stop and permit the proper subsequent operation of the column selecting mechanism. The present construction affords the great advantage of allowing the column selecting mechanism to be immediately re-operated if a mistake has been made in arresting it; or in allowing it to be operated after only one character has been printed, and this without any need of mental calculation such as has been necessary in some prior constructions under similar conditions where the number of the column at 130

which the carriage had been previously arrested had to be taken into consideration in calculating the new position at which it might be desired to arrest the carriage. In the 5 present instance the advantages above stated are due to the fact that the column selecting devices are moved bodily into and out of operative position.

The denominational tabulating mechanism will be described in connection with Figs. 1, 3, 7 and 9. The denomination stop levers 87, of which there are eight in the present instance, are arranged in an upright position forward of the post 30 in the parallel guide slots 31, said levers being pivoted on a rod 88 secured to the post, the upper end portions of said levers being confined in said guide slots 31, the lower ends fanning outward to some extent and passing behind 20 the bail 71. The denomination levers 87 are adapted to be swung on their common fulcrum so that their upper end portions will be thrown rearward to an operative position, filling in or closing the cutaway 25 32 in the post and intercepting the path of the forward stopping portions of the carriage stops 24, as shown in Fig. 3. The means for actuating the levers 87 comprise for each lever a link 89 pivotally connected 30 at its rear end to said lever and extending forward, the front end of the link being pivotally connected to an upright crank arm 90. Said crank arm is fixed to the right-hand end portion of a sleeve 91 which surrounds 35 and bears on one of the rock shafts 65. These sleeves 91, as will be understood from Fig. 7, are confined loosely between the left-hand supporting plate 66 and the hub portions of the crank arms 64 which are fixed 40 to the shafts near their right-hand ends. The crank arms 90, considered as a series, are progressively arranged on their respective sleeves 91, the crank arm 90 on the rear-most sleeve being nearest the right-hand side 45 of the machine while the others recede step by step toward the left. This enables the links 89 to be arranged in a series side by side in a substantially horizontal plane. Near its left-hand end each sleeve 91 has 50 fixed to it a forwardly extending crank arm 92 to the free end of which is pivotally connected the lower end of a key stem 93 that extends vertically upward through a guide opening in the plate 69, being provided at 55 its upper end with a key or button 94. The denominational keys 94 consequently are arranged in a row fore and aft of the machine at the left-hand end of the keyboard, occupying the same relative positions at this end 60 that the column selecting keys do at the opposite end.

The denominational keys 94 are provided with suitable indicating marks, in the present instance these marks being, reading 65 from the top downward, "7", "6", "5", "4",

"3", "2", "1", ".". It will be understood that the train of connections controlled by each of the keys 94 may be actuated without affecting the trains controlled by the keys 70. Each bell crank comprising arms 90 70 and 92 and the elongated hub portion 91 may be actuated by its key 94 without affecting the shaft 65 on which it bears and which acts as its fulcrum. Also each bell crank comprising arms 64 and 67 and the elongated pivot portion or shaft 65 may also be actuated by its associate key 70 without affecting the sleeve 91 which bears on it, and through which the shaft 65 extends. When one of the keys 94 is actuated it operates 80 through the train of devices comprising arm 92, sleeve 91, arm 90 and link 89, on the connecting stop lever 87, swinging the upper end of said lever rearward through the cutaway 32 into the path of the forward 85 edge portions of the stops 24. At the same time the lower arm of the lever 87 swings forward and acts against the universal bar or bail 71 which lies in front of the set of levers 87. As a result said bar is also swung 90 forward and acts through the train of devices comprising link 76, lever 77 and pin 79 to lower the clutch member 16 so that the carriage is automatically released. The release is so timed that after the actuated stop 95 lever 87 is positioned the carriage is freed and will move leftward until arrested in the predetermined denominational position by the engagement of the proximate carriage stop 24 with the actuated or projected stop 100 lever 87. It will be observed that the operating portion of this stop lever extends across the opening 32 and is so arranged that it is backed or reinforced on three sides; that is to say, above, below and at the front 105 of the portion or point which is directly engaged by the stop 24. As a result of this backing or reinforcing, liability of bending or distorting the stop lever, as a result of impact from the column stops, is reduced to 110 a minimum, thus doing away with objections found in prior constructions, in which as a result of such distortion the parts were either prevented from acting or else acted imperfectly producing inaccurate results. 115 When the depressed denominational key 94 is released the parts will be restored to normal position by restoring devices which comprise for each stop lever 87 and its key connections a coiled draw spring 95, the forward 120 end of which is hooked into a hole formed at the lower end of the stop lever, while the rear end of said spring is anchored to one of a series of hooks or projections 96 formed on a plate 97 which is secured by screws 98 125 to the rear face of the cross bar 28.

By my present invention I provide a very compact and comparatively simple construction, which has been found in practice to work efficiently in the reproduction of tabu- 130

lating work involving column skipping or selecting denominational or decimal operations. The mechanisms may be applied to the machine without interfering with other parts, and may be removed with little trouble, the principal operations to this end comprising the removal of the cross bar 28 and the plates 66, which provide the primary supports of both sets of mechanisms.

10 Various changes may be made without departing from my invention.

What I claim as new and desire to secure by Letters Patent, is:—

1. In a column selecting mechanism for typewriting machines, the combination of a 15 rotatable multiple stop, a support on which said stop is mounted, to afford movement independent of said support, a plurality of column stops operative to rotate said multiple stop, and means for moving said support to bring said multiple stop into co-operative relationship with said column stops.

2. In a column selecting mechanism for typewriting machines, the combination of a 25 carriage, a plurality of stops mounted thereon, a support movably mounted on the machine frame, a column selector on said support, and means for moving said support to bring said selector into co-operative relationship with the carriage stops, each of which is adapted to move it a limited extent independently of said support.

3. In a column selecting mechanism for typewriting machines, the combination of a 35 multiple stop, a pivoted support on which said multiple stop is movably mounted, a plurality of column stops each operative to move said multiple stop to a new position, and means for swinging said support on its 40 pivot to bring said multiple stop into co-operative relationship with said column stops.

4. In a typewriting machine, the combination of a movably supported frame, a multiple stop journaled on said frame, a plurality of column stops each adapted to rotate said multiple stop independently of said movable frame, and means for moving said 45 frame and carrying said multiple stop bodily into a position where it will coöperate with said column stops.

5. In a column selecting mechanism for typewriting machines, the combination of a 55 carriage, a stop bar thereon, a plurality of stops adjustably mounted on said bar, a column selector rotatable to a new position by each of said plurality of stops but normally out of operative relationship therewith, a pivoted frame on which said selector is mounted, means for moving said frame to carry said selector to operative position, and spring means operative on said pivoted frame and constantly tending to maintain 60 said selector in inoperative position.

6. In a column selecting mechanism for typewriting machines, the combination of a plurality of column stops, a coöperating multiple stop, a shaft carrying the same, a frame on which said shaft is journaled, a 70 support on which said frame is pivoted, means for swinging said frame on its pivot to move said multiple stop into and out of operation, and stop devices for limiting the swinging movements of said frame.

7. In a column selecting mechanism for typewriting machines, the combination of a plurality of column stops, a coöperating multiple stop, a shaft carrying the same, a 75 frame on which said shaft is journaled, said frame comprising a rock shaft, a bell crank fixed to said rock shaft, a crank arm fixed to said rock shaft, and a rod connecting one arm of said bell crank with said crank arm, fixed stop devices coöperative with said bell crank, and means for moving said frame to carry said multiple stop into and out of operative positions.

8. In a column selecting mechanism for typewriting machines, the combination of a 80 plurality of column stops, a coöperating multiple stop, a shaft carrying the same, a frame on which said shaft is journaled, said frame comprising a rock shaft, a bell crank fixed to said rock shaft, a crank arm fixed to said rock shaft, and a rod connecting one arm of said bell crank with said crank arm, stop devices for said frame, a plurality of key controlled actuators coöperative with 85 said rod to move said multiple stop into operative position, and a spring connected to the shorter arm of said bell crank and operative to restore said frame to normal position.

9. In a column selecting mechanism for typewriting machines, the combination of a 90 plurality of column stops, a coöperating multiple stop, a shaft carrying the same, a frame on which said shaft is journaled, said frame comprising a rock shaft, a bell crank fixed to said rock shaft, a crank arm fixed to said rock shaft, a rod connecting one arm of said bell crank with said crank arm, and a slotted extension on said bell crank which 95 coöperates with fixed stop devices, a plurality of key controlled actuators coöperative with said rod to move said frame to carry said multiple stop into operative position, and a stop barrel fixed to said first named shaft and provided with projections 100 which are progressively arranged and are adapted each to coöperate with the end of one of said actuators to limit turning movements of said multiple stop.

10. In a column selecting mechanism for typewriting machines, the combination of a 105 carriage, a plurality of column stops mounted thereon, a coöperating multiple stop, a shaft carrying the same, a frame on which said shaft is journaled, said frame 110

comprising a rock shaft, a bell crank fixed to said rock shaft, a crank arm fixed to said rock shaft, a rod connecting one arm of said bell crank with said crank arm, and a slotted 5 extension on said bell crank which co-operates with fixed stop devices, key controlled actuators co-operative with said rod, and carriage releasing devices operative by said rod.

11. In a column selecting mechanism for 10 typewriting machines, the combination of column stops; a co-operating multiple stop; a shaft carrying the same; a frame on which said shaft is journaled, said frame comprising a rock shaft, a bell crank fixed to 15 said rock shaft, a crank arm fixed to said rock shaft, and a rod connecting one arm of said bell crank with said crank arm; key controlled actuators co-operative with said rod; and carriage releasing devices operative 20 by said rod and comprising a bail, a link for transmitting movement from said rod to said bail, a release lever, and a second link connecting said release lever with said bail.

25 12. In a column selecting mechanism for typewriting machines, the combination of a plurality of tabulator stops, a multiple stop mounted for movement into and out of co-operative relationship with said tabulator 30 stops, and adapted to be moved in turn by each of them, means for moving said multiple stop into operative position, and a set of progressively arranged stops rigidly connected with said multiple stop and co-operative 35 with said means to variably limit the extent of actuation of said multiple stop by said tabulator stops.

13. In a column selecting mechanism for 40 typewriting machines, the combination of a plurality of tabulator stops, a rotatable multiple stop co-operative therewith, a series of progressively arranged stops rotatable with 45 said multiple stop, and key controlled devices each adapted to move said multiple stop into operative position and also to co-operate with one of said progressively arranged stops.

14. In a column selecting mechanism for 50 typewriting machines, the combination of a plurality of tabulator stops, a rotatable multiple stop co-operative therewith, a series of progressively arranged rotatable stops rigid with 55 said multiple stop, and means co-operating with said progressive stops to limit the turning movements of said multiple stop.

15. In a column selecting mechanism for 60 typewriting machines, the combination of a plurality of column stops, a multiple stop co-operative therewith, a shaft on which said 65 multiple stop is carried, a series of progressively arranged stops also carried by said shaft, spring means tending constantly to turn said shaft in one direction, a frame on which said shaft is journaled, and devices

for moving said frame and also for co-acting with said progressively arranged stops.

16. In a column selecting mechanism for 70 typewriting machines, the combination of a plurality of column stops, a multiple stop co-operative therewith, a shaft on which said 75 multiple stop is carried, a barrel fast on said shaft, and provided with a series of progressively arranged radial projections, a turning spring connected with said shaft, a frame on which said shaft is journaled, and key controlled actuators for moving said frame, said actuators co-acting also with said radial projections.

17. In a column selecting mechanism for 80 typewriting machines, the combination of a plurality of column stops, a rotatable multiple stop, a ratchet wheel rotatable with 85 said multiple stop, means for bodily moving said stop into operative position, and a spring-mounted pawl normally separate from said ratchet wheel but co-operative therewith when said multiple stop is operative.

18. In a column selecting mechanism for 90 typewriting machines, the combination of a plurality of column stops, a key controlled movable frame, a shaft journaled on said frame, a multiple stop fixed to said shaft, a ratchet wheel fixed to said shaft, a spring 95 barrel fixed to said shaft and provided with radial projecting stops, and a pawl co-operating with said ratchet wheel when said frame is moved to carry the multiple stop to a position to be turned by said column stops. 100

19. In a column selecting mechanism for typewriting machines, the combination of a carriage, a plurality of carriage carried stops, an upright shaft, a multiple stop thereon, a plurality of stop projections rigid 105 with said shaft, a movable support on which said shaft is journaled, and a series of horizontally arranged key controlled actuators for moving said support and for co-operating with said stop projections. 110

20. In a column selecting mechanism for typewriting machines, the combination of a carriage, a plurality of carriage carried stops, an upright shaft, a multiple stop thereon, a plurality of stop projections rigid 115 with said shaft, a movable support on which said shaft is journaled, a series of horizontally arranged key controlled actuators for moving said support and also for co-operating with said stop projections, and a stationary comb plate for guiding said actuators.

21. In a column selecting mechanism for 125 typewriting machines, the combination of a carriage, a plurality of stops, an upright shaft, a plurality of stop projections rigid with said shaft, a movable support on which said shaft is journaled, a series of horizontally arranged actuators for moving said support and for 130

coöperating with said stop projections, and trains of devices for operating said actuators, each train comprising a key, a key stem, a rock shaft, a crank arm on said rock shaft and to which said key stem is connected, a second crank arm on said rock shaft, and a link connecting said second crank arm with the associate actuator.

22. In a column selecting mechanism for typewriting machines, the combination of a plurality of column stops, a shaft, a multiple stop fixed on said shaft, a frame on which said shaft is journaled, said frame comprising a rod or shaft, and means for moving said frame comprising a set of key controlled actuators pivoted on said rod or shaft.

23. In tabulating mechanism for a typewriting machine, the combination of a carriage carried stop, a coöperative stop, a series of actuators for said coöperative stop, said actuators being horizontally disposed and arranged one above the other, keys for said actuators arranged in a series extending fore and aft of the machine, and trains of connections between said keys and said actuators, each train comprising a link, a rock shaft, and crank arms, one connecting the rock shaft with the link and the other connecting the rock shaft with the key, the points of connection of said links with said actuators being in substantially a vertical line while the points of connection of said links with said rock shafts vary progressively in distance from the ends of said rock shafts.

24. In a tabulating mechanism for typewriting machines, the combination of a key controlled stop lever, a coöperative stop, said lever being vertically disposed, a rock shaft, a crank arm fixed thereto, a link directly connecting said crank arm with said lever, a second crank arm fixed to said rock shaft, and a key stem pivoted to said second crank arm and provided with a key or button.

25. In a typewriting machine, the combination of a carriage, carriage stops mounted thereon, an upright post, denominational levers pivoted on said post, a movable frame pivotally supported from said post, a column selector mounted on said movable

frame, means for actuating said stop levers, and means for actuating said movable frame.

26. In a typewriting machine, the combination of a carriage, carriage stops, key actuated coöperating denominational stop members, key controlled column selecting stop devices also coöperative with said carriage stops, carriage releasing devices comprising a universal bar operative by said members, and a link connected to said universal bar and operative by said devices, said link being movable with said universal bar independent of said devices.

27. In a typewriting machine, the combination of a carriage; carriage stops; coöperating denominational stops; column selecting stop devices also coöperating with said carriage stops; means, for actuating said devices, comprising a plurality of key controlled rock shafts; and means for actuating said denominational stops, said last recited means comprising key actuated sleeves rotatably mounted on said rock shafts.

28. In a typewriting machine, the combination of a carriage, carriage carried stops, coöperating denominational stops, column selecting stop devices also coöperating with said carriage stops, means for actuating said devices comprising a plurality of key controlled rock shafts, crank arms, one fixed to each rock shaft, keys connected to said crank arms, a second set of crank arms, one fixed to each rock shaft, and links connected to said second set of crank arms; and means for actuating said denominational stops comprising a plurality of sleeves, one rotatably mounted on each rock shaft, crank arms, one fixed to each sleeve, keys connected to said last named crank arms, another set of crank arms, one fixed to each sleeve, and links connected to said last mentioned crank arms.

Signed at the borough of Manhattan, city of New York, in the county of New York and State of New York, this 15th day of Sept., A. D. 1914.

CLIO B. YAW.
